ABSTRACT

An electrical connector assembly having a male connector and a ring-shaped female connector interconnected by a flexible cable wherein the connector assembly is constructed in a one piece completely molded unit. The female connector has a plurality of sockets and guide holes formed in one surface of the ring.

ELECTRICAL CONNECTOR ASSEMBLY

BACKGROUND OF THE INVENTION

This invention relates generally to electrical connector assemblies and more particularly to a one-piece, completely molded electrical connector assembly.

In some applications, electrical apparatus must be located deeply within its associated equipment thereby making electrical connection thereto difficult. This is particularly true where access to the electrical apparatus can only be had through an extended restricted area, such for example as a well in the casting of a torpedo, mine or depth charge. In these situations mating between male connectors positioned in one apparatus and female connectors integral within a well in the mating apparatus can only be effected by a blind trial and error technique which sometimes results in damage to the connectors, such for example as impairment of the female contact members. In the past such damage could be repaired only by tediously chipping out and replacing the old female contact with a new one, rewiring the contact, and finally repotting the entire connection. Problems disclosed hereinabove are complicated by the rough handling of apparatus in which the connector is maintained.

Separate connector assemblies in lieu of integral arrangements have not proven practical since protuberances projecting from the electrical apparatus have rendered the use of standard connector assemblies physically impossible. Furthermore, when the application of the electrical equipment is in an underwater environment, short circuits may develop when separate connector assemblies are employed and water enters the assemblies.

SUMMARY OF THE INVENTION

Accordingly, it is an object of the present invention to provide an integrally formed electrical connector assembly.

An additional object of the present invention is to provide a one-piece, completely molded, waterproof electrical connector assembly.

It is a further object of the present invention to provide an electrical connector assembly connectable to an electrical connector having a centrally disposed protuberance.

Briefly, in accordance with one embodiment of this invention, these and other objects are obtained by providing a connector assembly having a flexible connector cable with male and female connector members integrally molded at either end thereto. A protuberance receiving aperture is formed in one of the connector members.

BRIEF DESCRIPTION OF THE DRAWING

A more complete appreciation of the invention and many of the attendant advantages thereof will be readily appreciated as the same becomes better understood by reference to the following detailed description when considered in connection with the accompanying drawings wherein:

FIG. 1 is a perspective view of the overall electrical connector assembly;

FIG. 2 is a cross-sectional view taken along line 2-2 of FIG. 1; and

FIG. 3 is a side view partially in cross-section, illustrating an application of the electrical connector assembly of the present invention.

DESCRIPTION OF THE PREFERRED EMBODIMENT

Referring now to the drawings wherein like reference characters designate identical parts throughout the several views and more particularly to FIG. 1, the electrical connector assembly generally designated as 10 is shown as including a flexible, multiple conductor cable 14 having at opposite ends thereof a female connector 12 and a male connector 16 connected thereto.

The female connector 12 is composed of an annular or ring-shaped body 18 formed of polyurethane and having a central

circular aperture 19. Molded within and circumferentially spaced around the ring-shaped portion 18 are a plurality of pin receptacles 20 which are preferably positioned equidistantly from each other. These may be of any conventional type, such for example as the standard tube type socket contacts shown in FIG. 2. Included intermittently among the sockets 20 and similarly molded within the ring portion 18 are a series of guide members such as holes 22, which may be equidistantly spaced apart, to position and guide associated apparatus during the coupling operation by means of corresponding projections formed on the apparatus in mating positions. The guide members 22 are composed of tube portions having a bore 24 opening into the lower surface 27 of the ring 18, and a cooperating counterbore 26 opening into the upper surface 28, the bores 24 and 26 both being of greater diameter than that of the receptacles 20.

Each receptacle 20 is suitable fastened to an end of a conductor 30 which extends from the flexible cable 14 by any conventional means such as soldering or crimping. The end portions of conductors 30 of cable 14 are fed into and lie within the lowermost portions of the ring 18 substantially adjacent to the lower surface 27 and may be molded into a fixed position therein. The inner surface 32 of the ring 18 is downwardly beveled as shown in FIG. 2 thereby providing greater space in order to accommodate the conductors 30.

The cable 14 is molded to the female connector 12 at a protuberance 34 which extends radially from the ring 18 and is integral therewith.

Similarly attached to the opposite end of cable 14 and integrally molded thereto is male connector 16 which may be one of a number of standard devices including a plurality of straight connector pins 36 projecting from a cylindrical casing 38. The connector pins 36 are to be slideably mated by means of an interference fit into a corresponding plurality of receptacles of a female connector (not shown). It is to be understood that each individual connector pin 36 is attached to a second lead end (not shown) of a conductor 30 in a conventional manner thereby associating with such connector pin 36 a corresponding socket 20.

By virtue of the integral relationship of the cable 14 and the female connector 12 and the subsequent encapsulation of the conductors 30 in the molded polyurethane ring 18 plus the unitary nature of the male connector 16 and cable 14, the conductors 30 are effectively sealed and thereby maintained water resistant.

Referring now to FIG. 3, the electrical connector assembly 10 is illustrated as providing a connection between two electrical devices 40 and 42. The device 40 is seated within a well 43 in a housing 45 and includes male contacts 44 positioned on a shoulder 46. Extending below the shoulder 46 is a central protuberance 48 which physically prohibited the utilization of socket members of prior electrical connector assemblies. The protuberance 48 passes through the aperture 19 thereby allowing the mating of the male contacts 44 and sockets 20. It can also be seen from FIG. 3 that the diameter of aperture 19 is determined by the size of the protuberance 48, having to be at least a small amount greater to allow the protuberance to pass therethrough.

Obviously, numerous modifications and variations of the present invention are possible in light of the above teachings such for example as replacing the sockets 20 with male pin contacts for mating with a female connector. It is therefore to be understood that within the scope of the appended claims the invention may be practiced otherwise than as specifically described herein.

What is claimed as new and desired to be secured by Letters Patent of the United States is:

1. A one-piece watertight electrical connector assembly comprising:
a flexible cable containing a plurality of electrical conductors;
a first electrical connector integrally molded to one end of said cable, and including a plurality of straight connector

pins, each pin fastened to one end of a corresponding one of said plurality of electrical conductors; a second electrical connector integrally molded to the other end of said cable and having a circular aperture centrally formed therein; a plurality of sockets formed in said second connector and circumferentially spaced around said aperture, each socket fastened to the other end of a corresponding one of said plurality of electrical conductors; and a plurality of guide members formed in said second connector, each comprising a tube portion having a bore opening

into a first surface of said second electrical connector and a cooperating counterbore opening into a second surface of said second electrical connector opposite said first surface, said bore and said counterbore being of greater diameter than said sockets.

2. The connector assembly of claim 1, wherein the inner face of said aperture is beveled.

3. The connector assembly of claim 1, wherein said plurality of sockets are equidistantly spaced around said aperture.
